EXPANSIBLE TOOL FOR REPAIRING
SPINDLES

Clifford De Lancey, Blackstock, S. C.

Application May 16, 1949, Serial No. 93,453

1 Claim. (Cl. 294—94)

1

This invention relates to an expandable hand tool adapted to be inserted in a tubular bolster and then expanded for removing the tubular bolster from a bolster case, in which it may have become stuck due to lack of lubrication or gummed oil residue, the bolster case being a usual part of a spindle of a type such as is used in spinning frames and which is commonly known to the trade as a medium #4KD spindle.

A certain type of bolster base such as is used on spinning frames and the like has a tubular bolster mounted for rotation therein and in which the spindle blade is supported, this type of bolster being commonly known as a McMullen bolster.

Now, due to friction and lack of lubrication, rotation of the bolster in the bolster case will cause the same to burn and adhere to the walls of the bolster case, as a result of which the usual tape which drives spindles of this type would merely slip in engagement with the conventional whorl of a spindle and the tubular bolster, along with the spindle blade, would remain stationary, thus requiring that the bolster be replaced in the bolster case.

Heretofore, in removing the tubular bolster from the bolster case it has been necessary to remove the bolster case from the conventional spindle rail or bolster rail and to then, by tapping the bolster case against an anvil or other hard object, gradually loosen the bolster in the bolster case and cause the same to fall therefrom by gravity. This often results in the base becoming damaged and in some instances the bolster case also becomes broken, and would also have to be replaced.

Also, upon again mounting the bolster case on the conventional bolster rail, it is necessary for an experienced operator to mount the bolster case on the bolster rail, insuring that the bolster case is accurately plumbed both above and below the horizontal plane of the bolster rail.

It is an object of this invention to provide a hand tool which is light in weight and may be produced economically and which has an expandable stem thereon adapted to be inserted in the open upper end of a tubular bolster which may have become stuck in a bolster case due to the reasons heretofore set forth and, by expanding the stem of the hand tool after inserting the same in the tubular bolster, the operator may pull the bolster out of the bolster case without the necessity of removing the bolster case from the bolster rail, thus decreasing the amount of time required to replace a bolster of this type.

It is another object of this invention to provide an expandable tool of the type described comprising a stem having an enlarged portion at one end thereof from which handle members

2

extend and its other end being circular in cross-section and this stem being cut substantially along its axis from its end adjacent the enlarged portion to a point a substantial distance from the circular end portion and then this end being curved outwardly to blend the portion cut along its axis with the circular end portion of the stem thus forming a concave cam surface on the stem. The enlarged portion of the stem has a semi-circular hole extending therethrough in which a wedging member which is semi-circular in cross section may be inserted, the flat surface of the semi-circular member tapering outwardly at the free end thereof to form a convex cam surface and the flat surface of the wedging member being adapted to slidably engage the flat surface of the stem cut along its axis so that, upon the stem being inserted in a bolster, the wedging member may then be inserted through the semi-circular hole in the enlarged portion of the stem and its tapering cam surface will engage the mating surface on the stem to thus cause the free ends of the wedging member and the stem to move outwardly in such a manner as to frictionally engage the interior surface of the bolster. An operator may then grasp the handle members and pull the bolster out of the bolster case without the necessity of removing the bolster case from the bolster rail.

Some of the objects of the invention having been stated, other objects will appear as the description proceeds, when taken in connection with the accompanying drawings, in which—

Figure 1 is a side elevation of the assembled expandable tool;

Figure 2 is a sectional plan view taken substantially along the line 2—2 in Figure 1;

Figure 3 is an enlarged sectional plan view taken along the line 3—3 in Figure 1;

Figure 4 is a vertical sectional view through the tool showing the same as being applied to a bolster for removing the same from a bolster case, the bolster case, bolster and a portion of a bolster rail being shown in cross section.

Referring more specifically to the drawings, the numeral 10 broadly designates the expandable tool which comprises a stem portion 11 which is substantially semi-circular in cross-section (Figure 3) and has an enlarged portion 12 integral therewith which is preferably circular in cross-section as shown in Figure 2 for substantially its entire length. However, its lower end in Figure 1 is enlarged to its full diameter and thus has a concave cam surface 14 which blends with the flat surface of the semi-circular stem 11.

The enlarged portion 12 of the stem 11 has a pair of handle members or rods 16 and 17 threadably imbedded therein which are adapted to be

grasped by an operator when the expandable tool 10 is being used in the manner to be later described. The enlarged portion 12 of the stem 11 has a bore 20 therein which extends substantially half way through the portion 12 and communicates with a substantially semi-circular bore 21. This semi-circular bore 21 is adapted to slidably receive an expansion rod or wedging member 22 which is semi-circular in cross-section and which has integral therewith an upper portion 23 which is circular in cross-section. This portion 23 has an enlarged knob portion 24 integral therewith which is adapted to be grasped by an operator for inserting the member 22 in the bore 20 and the hole 21 as shown in Figures 1 and 4. The semi-circular bore 21 serves to guide the wedging member 22 so that the flat surface thereof will engage the flat surface of the stem 11 to insure positive engagement of the cam 14 with the cam 26 to be described.

The lower end of the wedging member 22 is cut away on a slight arc thus providing a convex cam surface 26, which is substantially of the same configuration as the cam surface 14 in the stem 11 and these cam surfaces 14 and 26 are adapted to engage each other when the tool 10 is being used in the manner to be later described. It might be stated that the stem 11 of the tool 10 may be of a separate piece of material from the enlarged portion 12, if desired, and may be inserted in the bore 20 which, in this instance, would extend the full length of the enlarged portion 12 and may then be welded to the enlarged portion 12.

Referring to Figure 4, there is shown a portion of a bolster rail 30, which is slidably penetrated by a bolster case 31, the bolster case 31 having an enlarged portion 32 integral therewith adapted to engage the upper surface of the bolster rail 30. The bolster case 31 has an externally threaded portion 33 which has a nut 34 threadably mounted thereon and engaging the lower surface of the bolster rail 30 for securing the bolster case to the bolster rail 30. The bolster case 31 also has an outwardly extending right-angular portion 35 on which a conventional doffer guard 36 is oscillatably mounted.

The bolster case has a bore 40 extending substantially its entire length but being closed at its lower end as at 41. The right-angular portion 35 has a passageway 42 therein which serves as a lubricant receptacle and directs the lubricant to the bore 40 in the bolster case 31. A conventional tubular bolster 44 is snugly mounted within the bore 40 and has slidably mounted in its lower end a conventional pintle 45 and has a slot or oversized transverse bore 46 therein which is loosely penetrated by a pin 47 whose opposed ends are secured in the side walls of the tubular bolster 44 as by a pressed fit. The pintle 45 has a V-shaped cavity 50 therein for reception of the lower end of a conventional spindle blade not shown. The tubular bolster 44 has holes 48 therein through which lubricant may flow into the same.

It often happens that an operator will neglect to provide an ample supply of lubricant in the oil reservoir 34 of the bolster case 31, thus resulting in the tubular bolster 44 running dry, which will, eventually, cause the tubular bolster 44 to become burned or expanded to cause the tubular bolster 44 to adhere to the walls of the bore 40 in the bolster case 31. In this event, it is necessary to remove the tubular bolster 44 and to replace the same with a new bolster.

Now, in order to remove the bolster 44 from the

bolster case 31 after the bolster 44 has become stuck in the case 31, it is merely necessary to insert the stem 11 of the expandable tool 10 in the open upper end of the tubular bolster 44 and then the expansion rod 22 is inserted through the bore 20 and the semi-circular opening or hole 21 in the manner shown in Figure 4. The operator then forces the rod 22 downwardly to cause the cam surfaces 26 and 14 of the rod 22 and the stem 11, respectively, to engage one another and then by applying pressure to the upper end of the knob 24 in Figure 4, the cam surfaces will tend to urge the lower end of the members 11 and 22 apart from each other, thus expanding the lower end of the tool 10 and causing its outer surfaces to frictionally engage the inner surface of the tubular bolster 44, after which it is merely necessary for the operator to lift or to exert an upward pull on the handles 16 and 17 and, in so doing, the operator may remove the bolster 44 from the bolster case 31.

In the drawings and specification there has been set forth a preferred embodiment of the invention, and although specific terms are employed, they are used in a generic and descriptive sense only, and not for purposes of limitation, the scope of the invention being defined in the claim.

I claim:

An expandable tool for removing a tubular bolster from a bolster case comprising an elongated stem, semi-circular in cross-section for substantially its entire length, and having an enlarged portion at one end thereof, said stem being circular in cross-section at the end opposite from the enlarged portion, said stem being cut so as to provide a concave cam surface extending from the circular end of said stem and blending with the flat surface of the semi-circular portion of the stem, said enlarged portion being provided with a longitudinally extending circular bore extending a portion of its length, said enlarged portion also having a longitudinally extending semi-circular bore extending a portion of its length and communicating with the circular bore, the flat surface of said semi-circular bore being flush with the flat surface of said stem, a wedging member having a knob portion integral therewith and being circular in cross-section adjacent the knob portion and being semi-circular in cross-section for the rest of its length, said wedging member being adapted to be inserted into said bores in the enlarged portion so that the flat surface thereof will engage the flat surface of the semi-circular bore and the flat surface of the semi-circular stem, the lower end of said wedging member having an arcuate surface blending with its flat side and terminating at its rounded surface remote from the flat side; said arcuate surface being adapted to engage the concave cam surface of the elongated stem to wedge the stem and the wedging member in the bolster for extracting the bolster from the bolster case, and said semi-circular bore serving as a guide to cause positive engagement of the arcuate surface of the wedging member with the cam surface of the stem.
